(57) **CLAIM**

The ornamental design for a cart as shown and described.

DESCRIPTION

FIG. 1 is a top-front-left perspective view of a cart according to the claimed design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The dash-dot broken lines in FIG. 7 of the drawings define the bounds of the claim and form no part thereof. The dash-dot broken lines in the drawings illustrate features of the cart that form no part of the claimed design.

1 Claim, 7 Drawing Sheets
